Patented Feb. 19, 1918.

UNITED STATES PATENT OFFICE.

WALTER L. YOUNG, OF HARPER, CALIFORNIA.

EXPANSIVE DRILLING-BIT.

1,256,968.

Specification of Letters Patent. Patented Feb. 19, 1918.

Application filed April 9, 1917. Serial No. 160,869.

To all whom it may concern:

Be it known that I, WALTER L. YOUNG, a citizen of the United States, residing at Harper, in the county of Orange and State of California, have invented a new and useful Expansive Drilling-Bit, of which the following is a specification.

This invention relates to a drilling bit adapted for drilling a hole of greater diameter than the well casing through which the drilling bits are lowered into the hole, and is an improvement of a certain bit set forth in application Serial No. 2756, filed June 16, 1915; patented Dec. 5, 1916, No. 1207119.

15 An object of the invention is to produce a superior practical tool of this character to serve as a combined under-reamer and drilling bit.

As in my patented application the tool 20 comprises a non-resilient shifter in the form of a wedge lying within the body of the tool during the movement through the casing, said shifter being forced upwardly aslant to project beyond the outer periphery of the 25 body after said tool has passed below the casing, to thus crowd the cutting edge beyond the produced circular plane of the casing.

A particular object of the invention is to 30 provide means, in combination with a non-resilient shifter, to adjustably support the shifter in operative position and thereby regulate the size of the well hole to be bored, said means being automatically operated to 35 release the shifter and allow it to be retracted into the bore of the tool as said tool is drawn up into the casing upon withdrawal from the well.

Another object is to provide positive means 40 to move the shifter into operative extended position after the tool has passed below the casing.

The accompanying drawings illustrate the invention.

45 Figure 1 is a fragmental elevation partly in section on line x^1 , Figs. 2, 4 and 8, illustrating a drilling bit embodying this invention and in position below the casing at the bottom of a hole with the shifter wedge 50 latched in shifting position.

Fig. 2 is a fragmental elevation of the tool from the right of Fig. 1 with parts in a corresponding position.

55 Fig. 3 is an elevation illustrating the tool as it is being withdrawn from the hole. Solid lines show parts in position with the

shifter wedge just released and dot and dash lines indicate the fully retracted position.

Fig. 4 is a cross section of the tool looking up from line x^1 , Figs. 1, 2 and 3 with the 60 shifter wedge in extended position.

Fig. 5 is a cross section of the tool looking up from line x^5-x^8 , Figs. 1, 2 and 3, with the shifter wedge in retracted position.

Fig. 6 is a top view of the shifter wedge 65 detached.

Fig. 7 is a side elevation of the shifter wedge detached.

Fig. 8 is a plan section on line x^5-x^8 , 70 Figs. 1, 2 and 3, looking down.

Fig. 9 is a view showing two of the variable length operating legs that serve as positive means to move the shifter wedge into operative position.

The tool body 1 may be of any preferred 75 style having at its lower end a suitable cutting edge 2 and at its upper end the usual neck 3 and coupling pin 4 for connection to the auger stem 5. A longitudinally slanting chamber 6 is formed in the body 1 intermediate the cutting edge 2 and neck 3, said chamber opening out upon the periphery of the body upon the side opposite the cutting edge 2 and serving to slidably mount a shifter wedge member 7 which is guided 85 aslant relative to the axis of the tool by suitable guiding means as the aslant slide face 8.

Said open chamber 6 is bounded by the slanting slide wall or face 8 and side walls 9, which latter walls are upwardly tapering, 90 due to the oblique arrangement of the slide face 8, and terminate at the top in shoulders 10 that serve as an upper stop for the shifter wedge. In each of the side walls is provided a groove or recess 11, said recesses being arranged adjacent to and parallel with the slide-face 8, and forming ways in which tongues 12 of the shifter wedge seat to retain said wedge in position in the chamber. The shifter wedge is thus slidably mounted 100 in the chamber, projecting beyond the outer periphery of the body 1 when positioned at the top of said chamber and lying entirely within the outside traces of the body when positioned at the bottom of said chamber. 105

The shifter wedge when in extended position at the top of the chamber is adapted to contact with the wall of the well-hole for the purpose of holding the tool away from said wall at that side thereof and substantially in 110 central alinement with the hole, thus to maintain the opposite cutting edge 2 outside

of the produced plane of the shoe of the casing and in operative position during reciprocation of the tool.

To afford the requisite bearing surface 5 for contact with the wall of the well-hole said shifter wedge is provided with a shoe-portion 13 having side flanges 14 that serve to form an extensional outer face *a* which is upwardly tapering relative to the retaining 10 tongues 12, so that when the wedge is in position in the chamber with the tongues in register with the grooves 11 the face *a* will lie parallel with the axis of the tool. Said outer face *a* is of lateral convex conformation, the curvature of which substantially corresponds to the wall of the well which this tool is adapted to drill.

In order that the side flanges 14 and extensional face *a* of the shoe 13 may be 20 brought within the outside traces of the body 1 when the wedge is positioned at the bottom of the chamber, the longitudinal peripheral edges of the side walls 9 are cut away to form inclined faces 15, that extend aslant in the same direction as the face 8 from the bottom toward the top of the chamber 6, the depth of said cut-away portions at the bottom corresponding to the thickness of the flanges 14.

30 The shifter wedge serves as means to operate against the wall of the hole and force the tool body laterally to hold the cutting edge 2 in position to drill a hole of larger diameter than the well casing 35 through which the tool is lowered and it is desirable that said shifter wedge be adjustably supported in extended position at the top of the chamber in order that the distance which the shifter projects beyond 40 the periphery of the body may be varied, thus to regulate the lateral throw of the cutting edge 2 and consequently the size of the hole being drilled by the tool.

To this end the wedge is made self- 45 clutching throughout a determined part of its movement in the top of the chamber, so that as said wedge moves upward, it cannot be moved back until released. This self clutching feature also serves to afford 50 a step by step movement for the shifter wedge in case it is desired to move the same into commission at the top of the chamber by direct encountering with the plastic material at the bottom of the hole formed of 55 the loosened borings and water (not shown) as the first few strokes of the tool occur upon the beginning of the drilling operation. Said self-clutching means in the instance shown comprises an axially positioned latch bar 16 pivotally mounted at 60 17 in the chamber 6 near the bottom thereof, with which latch bar the wedge is adapted to engage at various positions along the slanting slide face 8.

65 The back of the wedge opposite the ex-

tensional shoe face *a* presents teeth 18 of a toothed face that lies intermediate side slide faces or runners 19, said toothed face extending substantially parallel with the slide faces 19 of the wedge. In the present construction the shifter wedge is provided with a mid-longitudinal gap 20 opening between the slide faces 19, in which gap is mounted a hardened steel block 21 which carries the teeth 18, said block being secured 75 in place by pins 22.

The latch bar is provided along its outer edge throughout a definite part of the upper portion thereof with teeth 23 that are in alinement with the teeth 18 of the shifter wedge when said latch bar is mounted in position within the chamber 6. In the slide wall 8 of the chamber is formed a mid-longitudinal groove 24 which is positioned opposite the gap 20 of the shifter wedge 85 when said wedge is in position in the chamber. This groove serves to house the latch bar 16 and extends upwardly aslant from said slide-wall at the bottom thereof and toward the axis of the body and has an upper portion that extends somewhat above the top shoulders 10 of the chamber 6, said upper portion opening out upon the periphery of the body above the wedge when in its topmost position in the chamber. 95

The latch bar is normally held pressed against the teeth of the shifter wedge by a compression spring 26 that is interposed between the upper end of the latch bar and a retaining plug 27 that forms the back of a chamber 28 for the spring, the arrangement of the teeth 18 and 23 being such that the shifter wedge is free to slide by the teeth of the latch bar when moved in an upward direction but is checked from moving in a downward direction until the latch bar teeth are moved out of alinement with the teeth 18. 100

It is desirable that automatic means be provided to release the shifter wedge and allow it to be retracted within the tool body upon withdrawal from the well and for this purpose the upper end of said latch bar is provided with an outwardly bowed portion or finger 29 that is positioned within the upper portion of the groove 24 when the latch bar is retracted with the wedge at the bottom of the chamber (see dot-and-dash position, Fig. 1) but which extends beyond the periphery of the body and into the produced plane of the casing when the bar is in position with its teeth 23 in engagement with the teeth 18 when the wedge is at the top of the chamber. 115

As the tool is raised into the casing the bowed finger 29 contacts with the bottom of the well casing *b* to depress the latch bar in opposition to the spring 26 and release the shifter wedge whereupon said wedge drops inwardly of the tool to the bottom of the 120 125 130

chamber, in which position it bears against the latch bar and holds the same, together with the finger 29, in fully retracted position in the groove 24. With the wedge and finger in this fully retracted position and entirely within the body of the tool, said tool may pass freely up through the casing *b*.

A lug 30 at the top of the body 1 and 10 upon the opposite side thereof from the chamber 6 is provided to hold the tool over in position so that the finger 29 will project sufficiently into the path of the casing *b* to afford requisite releasing movement as the 15 tool ascends into the casing upon withdrawal from the well. The top slanting face 31 will ride over the end of the casing in case the lug strikes said end upon passing into the casing.

20 When the tool is lowered into the well the shifter wedge will be positioned at the bottom of the chamber and lying entirely within the body 1, as shown in the dot-and-dash position of Figs. 1 and 3, in which position 25 the shifter wedge is out of commission in its retracted position so that the cutting edge 2 may lie within the circular plane of the casing as the tool passes down through said casing.

30 A special feature of this invention is the provision of positive means to force the shifter wedge into operative position at the top of the body after the tool has thus been lowered into operating position below the 35 casing *b* and for this purpose a depending operating leg 32 is suitably attached to the wedge as by pivot 22', and extends down through the lower axial bore 33 that establishes communication from the chamber 6 40 through the tool body to the bottom thereof. Said leg 32 is adapted to contact with the bottom of the well hole just ahead of the tool body and holds the wedge stationary, thus allowing relative movement between said 45 wedge and tool body as the body continues its descent to the bottom of the well hole. When the body reaches the bottom the wedge will be latched by teeth 18 and 23, in the upper position to which it has been 50 moved by the operating leg 32, in which position the convex shoe face *a* will bear against the wall of the hole to force the tool body laterally and maintain the cutting edge 2 in operative position to drill.

55 In the present instance the adjustable operating position in which the shifter wedge is supported to thus determine the size of hole to be bored is dependent upon the length of the operating leg 32 and in accordance 60 therewith legs of various lengths may be provided (see Fig. 9) to be readily attached as suits the operating conditions. For this purpose and also for purposes of ready assembling, the wedge is constructed of two 65 complementary pieces between which is posi-

tioned the toothed block 21. Said wedge pieces fit together with the inner longitudinal shoe faces *c* abutting one another and the block and pieces are held in place by the pins 22, 22'. The block 21 terminates 70 sufficiently above the bottom of the wedge to afford space in which to mount the eye 34 of one of the operating legs, the lowermost pin 22' serving to pivot said eye as well as position the pieces together.

75 From the foregoing it is thus seen that I have produced a simple and effective drilling bit of this character which is positively thrown into commission below the well casing to drill a hole of larger diameter than 80 said casing, and is automatically thrown out of commission upon ascent into the casing as the bit is withdrawn from the well, as well as being self-adjusting to drill well holes of 85 various diameters.

I claim:

1. A drilling bit comprising a body having a longitudinally slanting chamber opening out upon the periphery thereof, a cutting edge upon said body at the lower end thereof, a non-resilient shifter wedge mounted in said chamber and arranged to move in an aslant direction relative to the axis of said body so that said shifter wedge projects beyond the outer periphery of the body when 90 positioned at the top of said chamber and lies within said body when positioned at the bottom of said chamber, and means to adjustably support said shifter wedge at various heights relative to the cutting edge of 95 the tool to maintain said cutting edge in operative position.

2. In a well casing, a vertically rotating tool body having a longitudinally slanting chamber opening out upon the periphery thereof, a cutting edge upon said body at the lower end thereof, a non-resilient shifter wedge mounted in said chamber and arranged to move in an aslant direction relative to the axis of said body so that said shifter wedge projects beyond the outer periphery of the body when positioned at the top of said chamber and lies within said body when positioned at the bottom of said chamber, and retractable means to support said shifter wedge at the top of said chamber to maintain said cutting edge in operative position, said means being provided with an outwardly bowed portion to contact with the casing to thereby be automatically retracted 105 to release the shifter wedge and allow the same to move within the tool body as said body is drawn into the casing.

3. In a well casing, a vertically rotating tool body having a longitudinally slanting chamber opening out upon the periphery thereof, a cutting edge upon said body at the lower end thereof and opposite said chamber, a non-resilient shifter wedge mounted 110 in said chamber and arranged to move in an 115

aslant direction relative to the axis of said body so that said shifter wedge projects beyond the outer periphery of the body when positioned at the top of said chamber and lies within said body when positioned at the bottom of said chamber, a latch to support said shifter wedge in operative position at the top of said chamber, said latch being actuated by contact with the casing to release the shifter wedge and allow the same to move within the tool body as said body is withdrawn from the well.

4. In a well casing, a vertically rotating tool body having a longitudinally slanting chamber opening out upon the periphery thereof, a cutting edge upon said body at the lower end thereof and opposite said chamber, a shifter wedge mounted in said chamber and arranged to move in an aslant direction relative to the axis of said body so that said shifter wedge projects beyond the outer periphery of the body when positioned at the top of said chamber and lies within said body when positioned at the bottom of said chamber, an axially positioned latch bar pivotally mounted in the chamber at the bottom thereof, spring means to normally hold the latch bar in engagement with the shifter wedge and thus support said wedge in operative position at the top of said chamber, a bowed finger formed at the upper end of the latch bar and extending into the produced plane of the casing when said latch bar is in engagement with the shifter wedge, the latch bar being adapted to release the shifter wedge upon contact of said finger with the lower edge of the casing, when the tool body is withdrawn through said casing.

5. In a well casing, a vertically rotating tool body having a longitudinally slanting chamber opening out upon the periphery thereof, a cutting edge upon said body at the lower end thereof and opposite said chamber, a shifter wedge mounted in said chamber and arranged to move in an aslant direction relative to the axis of said body so that said shifter wedge projects beyond the outer periphery of the body when positioned at the top of said chamber and lies within said body when positioned at the bottom of said chamber, an axially positioned latch bar pivotally mounted in the chamber at the bottom thereof, spring means to normally hold the latch bar in engagement with the shifter wedge and thus support said wedge in operative position at the top of said chamber, the upper portion of said latch bar extending into the produced plane of the casing when said latch bar is in engagement with the shifter wedge, a lug at the top of said body and upon the same side as said cutting edge, said lug being effective to hold the body over in position so that said upper latch bar portion will contact with the lower end of the casing as the body ascends into said casing

to thereby move the latch bar to release the shifter wedge and allow the same to drop within the body.

6. In a casing, a vertically rotating tool body having a cutting edge for drilling a hole, a non-resilient shifter wedge adapted to operate against the wall of the hole to force the tool body laterally to drill a hole of larger diameter than said casing, and positive means to move the shifter wedge into operative position.

7. In a casing, a vertically rotating tool body having a cutting edge for drilling a hole, a non-resilient shifter wedge adapted to operate against the wall of the hole to force the tool body laterally to drill a hole of larger diameter than said casing, and positive means to move the shifter wedge into operative position, said means operating against the bottom of the hole.

8. In a casing, a vertically rotating tool body having a cutting edge for drilling a hole, a non-resilient shifter wedge adapted to operate against the wall of the hole to force the tool body laterally to drill a hole of larger diameter than said casing, and an operating leg adapted to contact with the bottom of the hole to hold the wedge stationary as the body is lowered, thus to cause relative movement between said wedge and body and force the wedge into operative position.

9. In a well casing, a vertically rotating tool body having a longitudinally slanting chamber opening out upon the periphery thereof, a cutting edge upon said body at the lower end thereof and opposite said chamber, a shifter wedge mounted in said chamber and arranged to move in an aslant direction relative to the axis of said body so that said shifter wedge projects beyond the periphery of the body when positioned at the top of said chamber and lies within said body when positioned at the bottom of said chamber, an axially positioned latch bar pivotally mounted in the chamber at the bottom thereof and provided with teeth along its upper portion, spring means to normally hold the latch bar pressed against the shifter wedge, and a toothed face on said wedge adapted to engage with said latch bar teeth to adjustably position the wedge and maintain said cutting edge in operative position.

10. In a well casing, a vertically rotating tool body having a cutting edge for drilling a hole beneath said casing of larger diameter than said body, a chamber in said body having a longitudinal slide-face extending aslant outward and upward to the axis of said body, a shifter wedge in said chamber and having a slide-face adapted to slide along said longitudinal slide-face to project said wedge beyond the periphery of the body at the top of the chamber and to withdraw said wedge within the body at the bottom of

the chamber, said shifter wedge being provided with a mid-longitudinal gap opening cut upon its slide-face, an axially-positioned latch bar pivoted in the chamber at the bottom thereof and extending up through said gap, said latch bar being adapted to engage with the wedge to support the same in operative position at the top of the chamber.

11. A drilling tool adapted to be operated through a casing to drill a hole of larger diameter than the casing, comprising a body having a chamber opening at one side of the body, a runner in the chamber, a guide-way extending aslant upward and outward in the chamber to shift the runner outward when the runner is moved upward in the chamber, said runner being adapted to extend beyond the surface of the body when at the upper end of the chamber and to be retracted by the guide-way when the runner is moved down in the chamber; a latch adapted to latch the runner in its extended position, and means adapted to impinge upon the casing to retract the latch when the tool is withdrawn through the casing.

12. A drilling tool adapted to be operated through a casing to drill a hole of larger diameter than the casing, comprising a body having a chamber opening at one side of the body, a runner in the chamber, a guide-way extending aslant upward and outward in the chamber, said runner being adapted to extend beyond the surface of the body when at the upper end of the chamber and to be retracted by the guide-way as it descends into the chamber; a latch adapted to latch the runner in its extended position, said latch pivoted to the body at the lower end of the guide-way and having smooth faces at its lower portion along which the runner may slide to hold the latch retracted when the runner is down; and means adapted to impinge upon the casing to retract the latch when the tool is withdrawn through the casing.

13. A drilling tool adapted to be operated through a casing to drill a hole of larger diameter than the casing, comprising a body

having a chamber opening at one side of the body, a runner in the chamber, a guide-way extending aslant upward and outward in the chamber to shift the runner outward as it moves upward in the chamber, said runner being adapted to extend beyond the surface of the body when at the upper end of the chamber and to be retracted by the guide-way as it descends into the chamber, a latch adapted to latch the runner in its extended position, and means adapted to impinge upon the casing to retract the latch when the tool is withdrawn through the casing, and a leg pivoted to the runner and adapted to impinge upon the bottom of the hole to hold the runner stationary at the latter descent of the tool in order to impinge upon the wall of the hole and to act upon the slideway to shift the bottom of the tool laterally.

14. The combination with a drilling tool body and a wedge member having a serrated face and adapted to coöperate therewith, of a latch pivoted in the tool body, and having a serrated face adapted to engage the serrated face of the wedge member and having a portion projecting from the tool body above the wedge member for retracting the serrated face of the latch from the wedge member to release the same, and means pivoted to the wedge member and adapted to contact with the bottom of the hole being drilled, to adjust the wedge member.

15. The combination with a drilling tool body and a wedge member having a serrated face and adapted to coöperate therewith, of a latch pivoted in the tool body and having a serrated face adapted to engage the serrated face of the wedge member and having a portion projecting from the tool body above the wedge member for retracting the serrated face of the latch from the wedge member to release the same.

In testimony whereof, I have hereunto set my hand at Los Angeles, California, this 2d day of April, 1917.

WALTER L. YOUNG.

Witness:

JAMES R. TOWNSEND.
